CLAIM

The ornamental design for a drinking glass with a twisted base, as shown and described.

DESCRIPTION

FIG. 1 is a top, perspective view of a drinking glass with a twisted base showing my new design;

FIG. 2 is a bottom, perspective view thereof;

FIG. 3 is a side elevation view thereof;

FIG. 4 is a side elevation view thereof;

FIG. 5 is a top view thereof;

FIG. 6 is a bottom view thereof;

FIG. 7 is a side elevation view thereof;

FIG. 8 is a side elevation view thereof;

FIG. 9 is a top elevation view thereof;

FIG. 10 is a cross section view showing a section taken along line 10-10 of FIG. 9;

FIG. 11 is a cross section view showing a section taken along line 11-11 of FIG. 9;

FIG. 12 is a cross section view showing a section taken along line 12-12 of FIG. 9;

FIG. 13 is a side elevation view thereof;

FIG. 14 is a cross section view showing a section taken along line 14-14 of FIG. 13;

FIG. 15 is a cross section view showing a section taken along line 15-15 of FIG. 13; and,

FIG. 16 is a cross section view showing a section taken along line 16-16 of FIG. 13.

The broken lines in FIGS. 9 & 13 depict the sectional indicia that form no part of the claimed design.

1 Claim, 16 Drawing Sheets
